[57] CLAIM

The ornamental design for a cab, substantially as shown and described.

DESCRIPTION

FIG. 1 is a perspective view as seen from the left front of the cab embodying our new design, the broken lines being for illustrative purposes only;
FIG. 2 is a front elevation view thereof;
FIG. 3 is a left side perspective view thereof, the right side of the cab is a mirror image of the left side shown herein;
FIG. 4 is a rear elevation view thereof; and
FIG. 5 is a top plan view thereof.
